US0D1098377S

(12) **United States Design Patent** (10) **Patent No.:** **US D1,098,377 S**
Dumonceaux (45) **Date of Patent:** **** Oct. 14, 2025**

(54) **ANTI-BACKFLOW PLATE**

(71) Applicant: **INDUSTRIAL FLOW SOLUTIONS OPERATING LLC**, New Haven, CT (US)

(72) Inventor: **Stephane Dumonceaux**, Burcy (FR)

(73) Assignee: **Industrial Flow Solutions Operating, LLC**, New Haven, CT (US)

(**) Term: **15 Years**

(21) Appl. No.: **29/825,872**

(22) Filed: **Feb. 7, 2022**

(51) **LOC (15) Cl.** **23-07**

(52) **U.S. Cl.**

USPC **D23/259**

(57) **CLAIM**

The ornamental design for an anti-backflow plate, as shown and described.

DESCRIPTION

FIG. 1 is a front, top, right side perspective view of the anti-backflow plate, in accordance with the present design; FIG. 2 is a rear, bottom, left side perspective view thereof; FIG. 3 is a front view thereof; FIG. 4 is a rear view thereof; FIG. 5 is a top view thereof; FIG. 6 is a bottom view thereof; FIG. 7 is a right side view thereof; and, FIG. 8 is a left side view thereof.

The dashed and broken lines represent portions of the anti-backflow plate that form no part of the claimed design.

1 Claim, 8 Drawing Sheets
